(21) Appl. No.: **29/142,571**

The ornamental design for a two-tone paint arrangement
applied to an automobile, as shown and described.

(22) Filed: **May 29, 2001**

DESCRIPTION

(51) LOC (7) Cl. **12-16**

FIG. 1 is a perspective view of a two-tone paint arrangement
applied to an automobile.

(52) U.S. Cl. **D12/196**; D12/86; D12/92;

FIG. 2 is a side view of the design shown in FIG. 1.

D12/400

FIG. 3 is a front view of the design shown in FIG. 1; and,
FIG. 4 is a rear view of the design shown in FIG. 1.

(58) **Field of Search** D12/196, 190,
D12/86, 90-92, 400; 296/185

The broken line showing of the environment is for illustrative
purposes only and forms no part of the claimed design.
The bottom view is not part of the claimed design. The two
differently shaded portions of the illustrated automobile
constitute two regions of differently colored paint applied to
the automobile.
